UNITED STATES PATENT OFFICE.

DAVID LLOYD GIBSON, OF PARNELL, AUCKLAND, NEW ZEALAND.

SKIP FOR HAULING COAL AND OTHER CARGO.

1,342,018.

Specification of Letters Patent.

Patented June 1, 1920.

Application filed January 27, 1920. Serial No. 354,343.

To all whom it may concern:

Be it known that I, DAVID LLOYD GIBSON, citizen of the Dominion of New Zealand, residing at 14 Balfour road, Parnell, Auckland, New Zealand, have invented certain new and useful Improvements in Skips for Hauling Coal and other Cargo, of which the following is a specification.

This invention relates to skips for hauling coal and other cargo out of or into ships, and provides a skip capable of being filled and emptied in either of two directions in an expeditious manner. The improved skip is specially adapted for use in the holds of ships, more particularly when cargo has to be hauled from a distance below decks to a hatch. The skip can also be readily loaded and unloaded by one man in the ship and another man on the wharf or in a railway truck or other vehicle.

The body of the skip has sloping ends and athwart its middle part is provided with a stiffener having an upper bar.

A bow pivoted to the sides of the skip below the center thereof is provided with a spreader bar just above the skip body, and also has a link or housing formed on its upper portion.

Levers pivoted on the spreader bar of the bow have projections at their outer ends, which pass through said bar and engage slots in the upper bar of the stiffener.

The inner ends of the levers are formed with slots which engage pins on a cross head, from which a stalk passes upward and has at its upper end a loop working freely in the link or housing of the bow.

When hoisting the skip the hook of the lifting gear is entered in the loop of the stalk, with the result that when the lifting strain is put on, the stalk is drawn upward in the link or housing of the bow, and causes the levers to lock the bow to the skip body.

When the lifting strain ceases, the stalk drops, and the levers are disengaged from the cross bar of the skip, whereupon the bow can be swung either way, on the latter.

In a modification, the bar is formed with an eye above the housing in which the loop of the stalk works, and when lifting, a rope is attached to the eye and another rope to the loop of the stalk. While strain is on both ropes, the skip body is locked to the bow, but immediately the rope attached to the loop of the stalk is slackened off the

levers are disengaged from the cross bar of the skip body and the latter is unlocked from the bow, whereupon the skip can be tipped.

Referring to the accompanying drawing 60 in conjunction with which the invention will be more particularly described:—

Figure 1 is a cross sectional view, and Fig. 2 a longitudinal sectional view of the improved skip.

Fig. 3 illustrates an alternative construction employed at the top of the bow.

Fig. 4 illustrates in perspective, portion of a locking lever and the bar carrying same.

The skip body is formed with sloping ends 1, and has sides 2 the upper edges 3 of which incline downward from the center to the ends 1.

A stiffener 4 having an upper bar 5 is 75 secured across the skip between the sides 2, midway of the ends 1, for the purpose of strengthening the body, the bar 5 having slots 6 formed therein one near each end.

The bow 7 is pivoted to the sides 2 below the center thereof and midway between the ends 1, said bow 7 being provided with a spreader bar 8 capable of clearing the bar 5 so as to allow the bow 7 to be moved to either side.

On the spreader bar 8 are pivoted levers 9 which terminate at their outer ends in projections 10 the latter passing through slots 8^a in the spreader bar 8 and engaging the slots 6 of the bar 5, when required.

The inner ends of the levers 9 are formed with slots 11, said slots being engaged by pins 12 on a cross head 13 at the lower end of a stalk 14.

The stalk 14 passes through a guide piece 95 15, which closes the lower end of the link or housing 16 at the top of the bow 7.

A loop 17 at the upper end of the stalk 14 works freely within the link or housing 16.

In use the hook of a lifting rope is made 100 to engage the loop 17 of the stalk 14, and immediately a strain is put on said rope, the loop 17 is drawn upward in the link or housing 16. This causes the projections 10 of the levers 9 to enter the slots 6 in the bar 105 5 of the stiffener 4, and so lock the bow 7 to the body of the skip.

The skip is then lifted and deposited where required, and immediately the lifting strain ceases, the stalk 14 drops down 110

and causes the projections 10 of the levers 9 to move upward out of the slots 6 of the bar 5.

The bow 7 is then free to swing on its pivots to either side until its rests on the edges 3 of the sides 2.

When discharging a loaded skip into (say for instance a railway truck) the skip is allowed to rest on the truck until the projections 10 of the levers 9 are disengaged from the slots 6 of the bar 5 to enable the bow 7 to be moved slightly to one side, whereupon on again putting a lifting strain on the hoisting rope, the skip is tipped and its 15 contents discharged.

In the modification shown in Fig. 3, an eye 18 is provided above the link or housing 16, and in practice a rope is attached to the eye 18, in addition to the rope attached to 20 the loop 17.

Both ropes take the lift, and to discharge the skip the rope attached to the loop 17 is slackened off. This permits the levers 9 to unlock the skip body from the bow 7 whereupon said body can be tipped in the bow 7 25 while suspended.

When hauling cargo at a distance below decks to a hatch the skip body is unlocked from the bow and tipped, and being hauled 30 while in the latter position acts as a scoop to pick up coal or other cargo.

The body of the skip can be of a size and shape to suit circumstances, and in some cases a truck can have a bow and central 35 cross bar fitted thereto as before described in order that cargoes can be loaded direct into or from a truck and the latter deposited where required.

What I do claim and desire to secure by 40 Letters Patent of the United States is:—

1. A cargo skip having a body fitted with a slotted central cross bar; a bow pivotally connected to said body and containing a slotted spreader bar; a stalk with a looped 45 upper end working in a housing at the top of the bow; and locking members connected to said stalk and operated by the latter to pass through the spreader bar and engage the cross bar of the body.

50 2. A cargo skip, having, a body fitted with a slotted central cross bar; a bow pivotally connected to said body and containing a

slotted spreader bar; levers pivoted to said spreader bar and adapted to engage the slotted cross bar of the body; and a stalk 55 connecting said levers with a loop working in a housing at the top of the bow.

3. A cargo skip, having, a body fitted with a slotted central cross bar; a bow pivotally connected to said body and containing a 60 slotted spreader bar; levers with projections at their outer ends and slotted inner ends pivoted on said spreader bar so that the projections can pass through the latter and engage the slots of the cross bar of the body; 65 a cross head with pins projecting therefrom connecting the slotted ends of said levers; and a stalk connecting said cross head with a loop working in a housing at the top of the bow.

4. A cargo skip, having a body fitted with a central cross bar slotted near each end; a bow pivotally connected to the sides of the body below the center thereof and containing a spreader bar slotted near each end; 75 levers with projections at their outer ends and slotted at their inner ends pivoted on said spreader bar, so that the projections can pass through the slots of the latter and engage in the slots of the cross bar of the 80 body; a cross head with pins projecting therefrom connecting the slotted ends of said levers; and a stalk connecting said cross head with a loop working in a housing at the top of the bow.

5. In a cargo skip, a bow pivotally connected thereto and containing a spreader bar; a housing at the top of said bow; members passing through said spreader bar; and a stalk connecting said members with a loop 90 in said housing.

6. In a cargo skip, a bow pivotally connected thereto and containing a spreader bar; a housing and an eye at the top of said bow; levers pivoted to said spreader bar; 95 and a stalk connecting said levers with a loop in said housing.

In testimony whereof I affix my signature in presence of two witnesses.

DAVID LLOYD GIBSON.
